AEROSOL SPRAY CONTAINER AND FILTER
Milo E. Webster, Rochester, N.Y., assignor to Bernz O
Matic Corporation, Rochester, N.Y., a corporation of
New York

Filed Nov. 7, 1963, Ser. No. 322,229
11 Claims. (Cl. 222—189)

This invention relates to an improved aerosol spray container.

Various fluids, such as, for example, paints, insecticides, cleaners, deodorants, and the like are marketed in aerosol spray containers which permits their dispensing and use as a fine aerosol spray.

The aerosol spray container generally comprises a pressurized container, as for example, a cylinder or can having therein the fluid to be dispensed and a propellant under pressure. A dip tube extends below the surface of the fluid and terminates at the bottom portion of the container and an aerosol spray valve, generally of the push-button type, is flow connected with the dip tube so that upon opening of the valve, as for example, by push-button operation, the pressure of the propellant forces the fluid from the container up through the dip tube and out through the aerosol valve in the form of a fine spray. The aerosol spray valve is provided with a terminal orifice which acts as the spray nozzle and is generally additionally provided with a primary orifice which is normally sealed but which becomes exposed, acting as the valve upon push-button operation. The orifices are in the form of constrictions having diameters which generally are larger than .020", as for example, between 0.20 and .040".

A major problem encountered in connection with the aerosol containers is the tendency of the aerosol valve to become plugged. This is particularly troublesome in connection with the dispensing of paint, and similar materials, but is also a problem in connection with the dispensing of other fluids. The plugging is generally caused by foreign particles or over-sized particles built up from the material being sprayed which sink to the bottom of the container and which are forced up the dip tube with the material being dispensed clogging one of the orifice constrictions in the aerosol spray valve. These particles which plug the orifice or orifices of the spray valve are firmly held in place by the pressure differential so that the plugging cannot be readily corrected and the container is rendered inoperative preventing further dispensing and use of the contents and resulting in severe customer dissatisfaction.

One object of this invention is a construction which reliably avoids the above-mentioned disadvantage in a simple and economical manner.

This and still further objects will become apparent from the following description read in conjunction with the accompanying drawing wherein:

FIG. 1 is an elevation view in cross-section showing an aerosol dispenser according to the invention; and

FIG. 2 is an elevation view of an insert for use in an aerosol container according to the invention;

FIG. 3 is a bottom view of the insert shown in FIG. 2;

FIG. 4 and FIG. 5 are fragmentary views of a container as is shown in FIG. 1, and showing alternative forms of construction for the container parts.

In the drawings like reference characters indicate corresponding parts.

In accordance with the invention, the plugging of aerosol valves is prevented by installing an insert in the conduit provided for conveying fluid to the orifice restriction in the valve (and which can be made up of a number of elements such as a dip tube, valve inlet and internal valve passageways). The insert effects a straining of the fluid

2

to prevent particles as would constrict the orifice from passing to the orifice. The insert is a solid piece disposed in close fitting relation with the walls of the conduit and the surface of the insert confronting the wall of the conduit has a plurality of axially extending grooves providing a like number of axially extending passageways each defined by one of the grooves and the overlying portion of the conduit. The passageways are smaller than the valve orifice constriction, so that the desired straining can be effected. The insert can be an integral part of the valve or can be a separate part suitably inserted in some part of the conduit, such as in a dip tube or in one of the valve passageways.

The grooves in the insert, conveniently, are rectangular having a depth dimension extending radially and a width dimension extending circumferentially. The smaller of said dimensions is preferably about 20% smaller than the diameter of the smallest orifice constriction of the valve. Commonly the smallest of said dimensions is desirably between about 0.010" and 0.015". The smallest orifice constriction is commonly about 0.020" diameter. These dimensions find particular application in the case of paint.

Referring to the embodiment shown in FIG. 1, 1 represents the pressurized container which in the embodiment shown is in the form of an aluminum cylinder, though any known or conventional container, as for example, the conventional "tin cans" may be used. The opening at the upper end of the container is sealed by the conventional crimped sealing cap 2 which is provided with the aerosol spray valve having the plastic push-button spray head 3 provided with the terminal spray orifice 4, the intermediate expansion chamber 5, and the primary orifice 6. The primary orifice 6 consists of a lateral hole extending through the wall of the stem portion 7 in communication with the intermediate expansion chamber 5. The aerosol spray valve is also provided with the hollow metal housing 8 joined by crimping to the cap 2. The housing 8 contains the spring 9 and the spring plunger 10 which is connected to the stem 7 of the spray button. The stem 7 extends through a central hole in the cap 2 provided with the gasket 11. The spring 9 normally forces the plunger 10 upward so that its upper edge contacts the gasket 11, and the primary orifice 6 is sealed by the gasket 11. When the spray button 3 is depressed, the spring 9 is compressed, and the primary orifice 6 exposed. Pressed into the lower end of the housing 8 is the dip tube 12 which can be formed of plastic material, as for example, polyethylene, polyvinylchloride or the like. The dip tube 12 extends to the bottom of the container 1 in the conventional manner, and as shown to the lowermost forward corner of the container.

The container 1 contains the liquid 15 to be dispensed, as for example, the paint, and is additionally charged with a propellant as for example liquefied propane, the propane vapor filling and pressurizing the upper space at 16. A conventional agitator ball or balls, for example, the glass agitator ball 17 is also provided in the container to aid the mixing of the paint by shaping prior to use.

In operation, the container is shaken and the agitator ball 17 aids in mixing the paint which generally consists of pigments, vehicle solids such as resin, and solvent. The terminal orifice 4 is then pointed at the surface to be coated and the spray head 3 depressed. The downward movement of the spray head 3 exposes the primary orifice 6 and causes downward movement of the plunger 10 and compression of the spring 9.

The pressure of the propellant vapor forces the paint up through the dip tube 12 past the plunger 8, which is provided with suitable clearance or openings for this

purpose, through the primary orifice 6 into the expansion chamber 5 and out through the terminal orifice 4 in the form of a fine spray which is used to coat the surface.

Upon release of the spray head 3, the action of the spring 9 in the conventional manner forces the spray head 3 upwardly so that the orifice 6 is masked by the gasket 11 shutting off the spray.

Normally, if a foreign particle were present in the paint, as for example a flake of aluminum in connection with aluminum containers or a piece of oxidized steel in connection with steel containers, or an agglomeration of pigment particles, or over-sized pigment particles or the like, the same, after sinking to the bottom of the container would be forced through the dip tube 12 clogging either the primary orifice 6 and/or the terminal orifice 4 rendering the container inoperative. The differential pressure would lock such particle in place over or in the orifice in question so that the situation could not be readily remedied except for example by exchanging the spray head.

In accordance with the invention, an insert 20, shown in detail in FIGS. 2 and 3, is utilized to prevent clogging of the valve. The insert 20 is an elongated, solid piece of plastic such as polyethylene, desirably low pressure polyethylene, having a plurality of axially extending grooves 21. The insert 20, as shown in FIG. 1, is installed in the lower end of the dip tube 12, wherein it is received as a press fit and is disposed in tight fitting relation with the wall of the dip tube 12.

In the embodiment shown in FIG. 4, the valve includes a plastic housing 22 which is crimped in place in the cap 2 to secure the valve on the container. The valve includes, as an integral part of the plastic housing 22, the insert 24. The end 25 of dip tube 12 is slid over the insert to provide the insert in the conduit from the fluid in the container to the valve, all to provide straining action of the insert according to the invention.

In the embodiment shown in FIG. 5, the insert as well as the confronting conduit wall portion, which with the slots in the insert define the passageways provided for straining, are included as parts of the valve assembly. The valve is provided with an insert 24 as an integral part thereof, just as in the case of the embodiment shown in FIG. 4. Further, however, the valve is outfitted with the nipple 25 which is in tight fitting relation with the insert 24, the inside walls of the nipple 25 overlying the grooves 21 so as to provide passageways for straining. The dip tube 12 is slid over the nipple 25 and is secured thereon by the enlargement 26 of the nipple.

With the construction in accordance with the invention, a particle as would tend to plug or clog an orifice constriction of the valve would merely become wedged against an entrance to a groove 21 and would not interfere with operations as paint or other fluid could be forced through the other grooves 21. Any particle passing through a groove 21 could not clog in the orifices 6 or 4 as these latter orifices are of a larger size than the perforations 14. In the embodiment shown in FIG. 1, even if all the grooves 21 become covered by foreign particles, this would not present a serious problem as further agitation and the action of the agitator ball would dislodge such particles so that the container could be rendered again operative. Commonly, a lodged particle, regardless of the position of the insert 21 will become dislodged because of pressure equalization across the insert.

The inside diameter of the conduit in which the insert is installed can be about $5\frac{1}{2}$ " and the insert can be of somewhat greater diameter to provide a press fit. About 20 grooves can be formed in the insert.

Advantages of construction according to the invention include low cost and dependability. Further the construction can be incorporated into the construction of existing or previously known parts of the container or it

can be merely added to known container parts, such as by merely placing the insert in the dip tube.

The improvement in accordance with the invention is, of course, applicable in connection with any of the known or conventional aerosol spray containers provided with any of the known or conventional aerosol spray valves and charged with any of the conventional aerosol materials, and conventional propellents, as for example, fluorinated hydrocarbon, such as the various freons used for this purpose.

While the invention has been described in detail with reference to specific embodiments shown, various changes and modifications which fall within the spirit of the invention and scope of the appended claims will become apparent to the skilled artisan. The invention, therefore, is only intended to be limited by the appended claims or their equivalents wherein I have endeavored to claim all inherent novelty.

What is claimed is:

20. 1. In an aerosol spray container comprising a pressurized container having therein a fluid to be dispensed and a propellant under pressure, a valve for discharge of fluid from the container mounted on the container, said valve having at least one orifice constriction, a conduit for conveying fluid from within the container to the orifice constriction for passage therethrough, the improvement which comprises a solid insert positioned in said conduit in close fitting relation with the walls thereof, the surface of the insert confronting the conduit wall having a plurality of axially extending grooves providing a like number of axially extending passageways each defined by one of said grooves and the overlying portion of the conduit and communicating the portion of the conduit on one side of the insert with the portion of the conduit on the other side of the insert, said passageways being smaller than said orifice for straining the fluid to prevent particles as would constrict said orifice from passing to the orifice.
25. 2. Improvement according to claim 1, wherein said conduit includes a valve inlet and a dip tube having one end thereof communicating with the valve inlet and the other end thereof communicating with the fluid in the container, said insert being disposed in said dip tube.
30. 3. Improvement according to claim 1, wherein said insert is integral with the valve housing.
35. 4. In an aerosol spray container comprising a pressurized container having therein a fluid to be dispensed and a propellant under pressure, a valve for discharge of fluid from the container mounted on the container and having a valve inlet disposed within the container for receiving fluid from the container, said valve having at least one orifice constriction, a dip tube within the container having one end thereof in flow communication with the said valve inlet and the other end thereof disposed below the surface of the fluid in the container for receiving the fluid for conveyance to the valve inlet, the improvement which comprises an insert disposed in said dip tube in tight fitting relation with the walls thereof, the surface of the insert confronting the dip tube having a plurality of axially extending grooves providing a like number of axially extending passageways each defined by one of said grooves and the overlying portion of said tube and communicating the portion of the dip tube on one side of the insert with the portion of the dip tube on the other side of the insert, said passageways being smaller than said orifice for straining the fluid to prevent particles as would constrict said orifice from passing to the orifice.
40. 5. Improvement according to claim 4 in which said aerosol spray valve has a primary and terminal orifice and in which said perforations are smaller than both said orifices.
45. 6. Improvement according to claim 4 in which said fluid is paint.
50. 7. Improvement according to claim 4, said passageways having a depth dimension extending radially and a width
55. 8. Improvement according to claim 4, said passageways having a depth dimension extending radially and a width
60. 9. Improvement according to claim 4, said passageways having a depth dimension extending radially and a width
65. 10. Improvement according to claim 4, said passageways having a depth dimension extending radially and a width
70. 11. Improvement according to claim 4, said passageways having a depth dimension extending radially and a width
75. 12. Improvement according to claim 4, said passageways having a depth dimension extending radially and a width

dimension extending circumferentially, the smaller of said dimensions being between about 0.010 and 0.015".

8. Improvement according to claim 6, said passageways having a depth dimension extending radially and a width dimension extending circumferentially, the smaller of said dimensions being between about 0.010 and 0.015".

9. Improvement according to claim 8 wherein the smallest orifice constriction in the valve being greater than about 0.020" diameter.

10. In an aerosol spray container having a dip tube in flow communication with a discharge opening from the container, the improvement comprising an insert disposed in said dip tube in tight fitting relation with the walls thereof, the surface of the insert confronting the dip tube having a plurality of axially extending grooves providing a like number of axially extending passageways each defined by one of said grooves and the overlying portion of said tube and communicating the portion of the dip tube on one side of the insert with the portion of the dip tube

on the other side of the insert, the said passageways being of a smaller size than the smallest cross-sectional size of the flow path from the dip tube through the discharge opening.

5 11. Improvement according to claim 10, wherein the dip tube is expansible and the insert press fit therein and the tube elastically grips the insert and prevents displacement thereof.
